DESIGN FOR A DRESS

Blanche Price, Chicago, Ill.

Application January 11, 1941, Serial No. 97,986

Term of patent 3½ years

To all whom it may concern:

Be it known that I, Blanche Price, a citizen of the United States, residing at 433 Wrightwood Avenue, Chicago, in the county of Cook and State of Illinois, have invented a new, original, and ornamental Design for a Dress, of which the following is a specification, reference being had to the accompanying drawing, forming part thereof.

I claim:

The ornamental design for a dress, substantially as shown.

BLANCHE PRICE.
